TRANSMISSION SYSTEM FOR A PRESSURE-
OPERATED MEMBER SUCH AS A HY-
DRAULIC PRESS

David Sciaky, Paris, France

Application April 12, 1935, Serial No. 16,107
In Germany April 20, 1934

1 Claim. (Cl. 60—54.5)

The object of the present invention is to utilize fluid under pressure in a scientific manner by economizing the amount of motive fluid used.

The invention is further intended to provide a hydraulic intensifier that is essentially simple and comprises masses of small inertia in motion.

A further object of the invention is to render it possible to put the apparatus out of action at the conclusion of each operation so that these operations shall follow each other periodically or at definite long or short intervals.

Still another object of the invention is to eliminate the necessity for powerful compressors, systems of large diameter piping and large hand relief-valves as well as valves or cocks.

Lastly the invention aims at considerably reducing the space required for the installation.

Installations by which the foregoing objects are realized possess the features set forth in the specification below and in the claim annexed to the said specification.

The preferred constructional forms of the invention are shown, by way of example, in the accompanying drawings wherein:—

25 Fig. 1 is a diagrammatic view of a hydraulic transmission system according to one constructional form of the invention.

Fig. 2 is a diagrammatic view of a second form of practical construction, of a hydraulic transmission system.

The system illustrated in Fig. 1 includes two hydraulic intensifiers, one 6—13 operating at low pressure and the other 7—16 at high pressure, these being intended to operate the machine 50, which may be a hydraulic press, a welding-machine, or the like. Compressed air, representing the motive power, is supplied from source A and is controlled by the hand-operated valves 2 and 3, located in the feed pipes of the low and high pressure intensifiers respectively.

Normally, the pistons 10 and plunger 14 of the two intensifiers are at their highest positions. When the 4-way cock 4 is adjusted to the position shown in Fig. 1, the compressed air arriving by the pipe 1 enters the upper chamber of the cylinder 6 and acts on the piston 10 to free down the plunger or ram 11, which has a large working surface, and which compresses the fluid in the lower chamber which then passes from the space 13 through pipe 35 and is forced into the chamber 16 and then into the operating cylinder 19 of a machine. The ram 50 of the machine is thus forced down to press or operate on the work-piece in the machine.

55 If, at this moment, the 4-way cock 5 is turned

so as to bring it into the position indicated in dotted lines, the compressed air passes through the aperture 24 of the cock 5 and enters the upper chamber of the chamber 7 to act on piston 14 and the plunger 15 is forced down and during the first part of its movement it breaks the communication between the enclosed spaces 13 and 16. Thereafter, the plunger 15, which is of small diameter relatively to its pneumatic piston 14, produces in the cylinder 19 the high pressure 10 desired.

If the two 4-way cocks are turned to their other positions the pistons 10 and 14 can return to their normal raised positions owing to the establishment of communication between the upper chambers of the cylinders 6 and 7 and the free air and owing to the admission of compressed air into the spaces beneath these pistons 10 and 14 respectively, through the inlets 27 and 26.

In order to render the operation of the high-pressure intensifier automatic and positive, the system of Fig. 1 is supplemented by an automatic control device, which is in turn controlled by the low-pressure intensifier and controls the high-pressure one. This device takes the form of a 25 hydraulically controlled valve with a hydraulic ram 20, the cylinder of which is connected with the pipe 35 connecting the lower cylinders 13 and 16 of the low- and high-pressure intensifiers. The plunger 20 is coupled to the handle 22 of the 30 cock 5 and is normally pulled into its cylinder by coil springs 21, the tension of which may be regulated by means of the screws 51.

This device functions as the result of the excess pressure set up in the fluid, when acted on 35 by the plunger 11, at the moment when the movable ram 50 of the receiver 19 commences to compress the work. At this moment the piston 20 is forced outwards from its cylinder and operates the handle 22 of the cock 5 and, in consequence, 40 causes the high-pressure intensifier to function. In this way the working pressure is automatically obtained at whatever position the ram 50 may be in and independently of the thickness of the 45 work-pieces to be operated on.

The installations comprise also a liquid source 8 that supplies liquid, through the pipe-system 9, to the cylinders 13 and 16 of the low-and-high pressure intensifiers. This supply of liquid is effected by a port 12, provided for the purpose in the plunger 11 and coinciding with the inlet opening of the pipe 9 when the said plunger 11 is at the upper extremity of its travel, that is to say, in normal position.

55

In the constructional form, illustrated in Fig. 2, the means for automatic control of the high-pressure intensifier consists essentially of two valves 28 and 29 carried by a movable rod 30; this rod 30 and the valves 28, 29 constitute a distributor that is actuated by a membrane or diaphragm 31 fitted in a chamber 32. At its other end, the rod 30 is acted on by a spiral compression spring 33, the tension of which can be adjusted. The compressed-air is supplied to inlet 44 through a stop valve 3, while the outlet 43 communicates with the space above the piston 14 of the pneumatic cylinder 7 of the high-pressure intensifier; the space below the piston in this pneumatic cylinder being supplied from the cock 4 of the low-pressure intensifier through the conduit 21. The distributor or hydraulically controlled valve has also an outlet at 47 communicating with the outer air. The manner in which this system functions is as follows:

As soon as the movable ram 50 of the receiver 19 commences to compress the work, the increased pressure in the liquid caused by the plunger 11 causes a deformation of the diaphragm 31, which, through the action of the rod 30 closes the valve 28 and opens valve 29. The compressed air, arriving through inlet 44, can pass through pipe 43 and enter into the upper space of the cylinder 7. When the cock 4 is restored to its normal position, the upper space above the piston of the cylinder 6 is put in communication with the free air and the lower spaces (below the pistons) of the cylinders 6 and 7 are subjected to pressure through the pipes 21. The piston 10 then returns to its normal raised position and the release of the excess pressure which previously existed in pipe 35 causes the restoration of the diaphragm 31 to its normal position. The spring 33 then closes the valve 29 while also opening the valve 28 and putting the upper space of the cylinder 7 in communication with the outer air, thus en-

abling the piston 14 to resume its inoperative position.

The motive fluid employed in these installations may be compressed air or any other suitable agent. For purposes of transmission, any fluid appropriate for the end in view may also be made use of.

The invention may be applied to operate any device for the utilization of pressure, such as, for instance, a hydraulic press, locking-devices for butt-welding machines, electrodes of spot-welding machines and also any other machines in which one or more workpieces require to be fixed so as to be compressed or otherwise operated on.

What I claim as my invention and desire to secure by Letters Patent is:—

In a transmission system for pressure-utilizing means such as hydraulic presses; a source (A) of fluid under pressure; a low-pressure hydraulic intensifier (6, 13) supplied from the source (A); a high-pressure hydraulic intensifier (7, 16) supplied from the source (A), comprising a cylinder (16) and a movable element such as a piston and ram (14, 15) reciprocating within the said cylinder (16); means of intercommunication (35) between the low-pressure intensifier (6, 13) and the high-pressure intensifier (7, 16), the said means discharging into the cylinder of the high-pressure intensifier and being controlled by the said movable element, such as the piston (14, 15) of the said high-pressure intensifier; an automatic pressure responsive control device (20, 21) controlled by the pressure of the low-pressure intensifier (6, 13) and, in turn, controlling the operation of the movable element of the high-pressure intensifier to bring the said high-pressure relay (7, 16) into operation when the low-pressure intensifier has operated; a receiver (19) actuated, in succession, by the low-pressure intensifier (6, 13) and by the high-pressure intensifier (7, 16) and actuating the pressure-utilizing means.

DAVID SCIAKY.
